UNITED STATES PATENT OFFICE.

HALLER H. DAWSON, OF CLARKSBURG, WEST VIRGINIA, ASSIGNOR TO HAZEL-ATLAS GLASS CO., OF WHEELING, WEST VIRGINIA, A CORPORATION OF WEST VIRGINIA.

DESIGN FOR A DRINKING GLASS.

Application filed February 1, 1928. Serial No. 25,118. Term of patent 7 years.

To all whom it may concern:

Be it known that I, HALLER H. DAWSON, a citizen of the United States, residing at Clarksburg, in the county of Harrison and State of West Virginia, has invented a new, original, and ornamental Design for Drinking Glass, of which the following is a specification, reference being had to the accompanying drawing, forming part thereof.

Figure 1 is a side elevation of a drinking glass; and

Figure 2 is a sectional view thereof taken on line 2—2 of Figure 1, showing my new design.

I claim:

The ornamental design for a drinking glass, as shown.

HALLER H. DAWSON.
